LIQUID PUMPING APPARATUS

Fausto Arzalluz Solis, Habana, Cuba, assignor to
 Julian Solis Sanchez and Alberto Solis Cepero,
 both of Ranchuelo, Cuba

Application January 24, 1947, Serial No. 724,102

4 Claims. (Cl. 103—175)

1

This apparatus relates to apparatus for pumping liquids, and it has for its object to provide an apparatus of that kind adapted to pump water in a continuous stream from deep wells, rivers, dams, ponds, etc.

It is a well-known fact that single action pumps operate intermittently, that is, they do not cause a continuous stream of liquid, owing to that the same suck the liquid up during the movement of their plunger in one direction while they force the liquid out in the opposed movement of their plunger.

Such disadvantage is obviated by the mechanical apparatus of this invention, which comprises a vertical cylinder provided with two plungers, the cylinder being in communication at each opposed end by a tube having a check valve with a water in-take also provided with a check valve and with the liquid outlet, whereby in the movement of both plungers at a time in one direction, one plunger sucks up the liquid while the other plunger forces out the previously sucked up liquid, and in the opposed movement of both plungers at a time, the plunger that previously sucked up the liquid will now force out the liquid while the other plunger that previously forced out the liquid will now suck up the liquid, with the result that a continuous stream of liquid is forced out through the outlet that is common to both tubes connected with the cylinder, the whole being a simple structure formed by commercial tubes and metal parts which can be economically assembled at farms or other places for pumping water from deep wells, rivers, etc., with a minimum requirement of power which can even be applied by hand.

The invention is described with reference to the figures of the accompanying drawings, of which:

Fig. 1 is an outer elevational view of the apparatus of this invention.

Fig. 2 is a diametral vertical section view of same, showing the two plungers at their lower end position.

Fig. 3 is a similar view to that of Fig. 2, showing the two plungers at their upper end position.

Fig. 4 is a horizontal view on line 4—4 of Fig. 1.

And Fig. 5 is a detailed diametral vertical section view of the plungers-carrying cylinder illustrating the structure of one of the plungers.

The apparatus of this invention is composed of a cylinder 1 preferably made of brass and of a diameter of 3 inches and a length of 32½ inches, which is open at both ends where it is provided with an outer 1-inch fine thread adapted to

2

threadedly receive threaded brass caps 2 and 3 of a thickness of 2 inches and a diameter of 3½ inches. The lower cap 2 has a central threaded opening adapted to threadedly receive a liquid sucking galvanized tube 4 of an outer diameter of 1½ inches and ending inferiorly in a water in-take casing 5 having an inner vertical check valve 6 and a strainer 7 at the inlet opening.

The tube 4 is connected intermediate its ends 10 through a coupling joint 8 with an elbowed tube 9 connected with the inlet opening of another casing 10 having an inner vertical check valve 11 and the outlet opening of which is in turn connected with a cast iron vertical tube 12 extending upwardly beyond the top end of the cylinder and being connected through a galvanized universal joint 13 with the left side branch of a cast iron T-shaped member 14 having on top thereof an outlet orifice of 1½ inches to lead the raised liquid to the desired place. The central branch of the member 14 is adapted to give way therethrough to the brass stem 15 of a thickness ½ inch, which is connected to the upper plunger and said central branch of member 14 is provided with a lower outer thread to engage a threaded nipple 16 having a conical upper end and a cylindrical lower end and which is secured by autogenous welding to the cap 2. The latter having on top thereof a reduced extension 2'.

15 The cap 2 and its extension 2' have a central hole to loosely allow the passage of the stem 15 about which there is disposed within the hole of cap 2 and its extension 2' a press-joint formed by an upper brass cylindrical press member 17 20 screwed on the inner threaded surface of the extension 2', a packing refilling 18 and a lower threaded nut 19 screwed on the innerly threaded surface of the cap 2 thereby closing the press-joint inferiorly.

25 The cylinder 1 has at a side of its top portion a flow opening 20 of 1½ inches, to which is welded the cast iron T member 21 connected through its lower threaded opening with the vertical galvanized iron tube 22 ending inferiorly at a level 30 with the valve casing 5 in another water in-take casing 23 having an inner vertical check valve 24 and a strainer 25 at the inlet opening, and the T member 21 is connected at its top threaded opening with a casing 27 having an inner vertical check valve 28 and which in turn is connected at its top opening and through a threaded nipple 29 with the universal joint 30 screwed on the end of the right-side branch of the T-shaped member 14 to lead raised liquid.

35 Within the cylinder 1 are mounted two plung-

ers connected by the brass rod 31. The upper plunger is suspended from the lower end of the stem 15 and the lower plunger is suspended from the lower end of the rod 31. The lower plunger is composed (Fig. 5) of an outerly threaded core 32 having a lower head 32', on which there are mounted four leather washers 33, 34, 35 and 36 disposed alternately with cast iron ring-nuts 37, 38, 39, 40 and 41 which are screwed on the core 32, with the peculiarity that the lower leather washers 35 and 36 are curved downward at their periphery and the upper leather washers 33 and 34 are curved upward at their periphery, and on the top end of the core 32 there is screwed the nut 42 that presses on the upper ring 31, the core having a top central hole 43 with a threaded surface to threadedly receive the threaded end of the rod 31.

The upper plunger is formed similarly, only that the upper leather washers 33' and 34' are curved downward at their periphery and the lower leather washers 35' and 36' are curved upward at their periphery, the head of their core having a threaded hole to engage the upper threaded end of the rod 31 and the core having a threaded hole to engage the lower threaded end of the stem 15.

The operation of this apparatus is as follows: Assuming the suction pipes fed and the lower plunger being at the lower portion of the cylinder 1 (Fig. 2), the lower plunger in its upward movement produces suction through valve 6 while atmospheric pressure maintains the valve 11 closed, whereupon the space inferiorly to the lower plunger within the cylinder 1 is filled with water. In said upward movement the upper plunger forces through opening 20, T member 21, nipple 26, valve 28, nipple 29, joint 30, right branch of T-member 14 and top outlet opening of member 14, the liquid that occupied the space of cylinder 1 situated directly above the upper plunger, the valve 24 remaining closed. On the contrary, in its next or downward movement, the upper plunger produces suction through tube 22 and valve 24, the space of cylinder 1 remaining above said upper plunger becoming filled with water, and the valve 28 remaining closed by atmospheric pressure, and the lower plunger forces the water that was contained in the space of cylinder 1 beneath the lower plunger out through the elbowed tube 9, valve 11, vertical tube 12, union 13 and left branch of T-member 14, the valve 6 remaining closed. As the lower plunger reaches the lower end of cylinder 1, the previous movement cycle is repeated, and so forth.

The result is that in the opposed movements, two streams of water come out through the upper outlet tube and gather uninterruptedly to form a continuous stream. The stem 15 is adapted to receive the action of a power transmitted which may be either mechanical or manual.

It is obvious that changes may be made in the construction details of the tubes connecting the cylinder to the water in-takes and to the outlet

for raised liquid, without thereby altering the essential character of the invention which is such as claimed hereinafter.

What I claim is:

- 5 1. A mechanical apparatus for raising a continuous stream of liquid, comprising a cylinder having perforated threaded caps at its ends, tubes connecting orifices in the opposed ends of the cylinder with two spaced apart liquid intakes each provided with a check valve, a three-branch member for raised liquid outlet which is mounted at its central branch on the upper cap of the cylinder, a stem loosely passing across the central branch of said three-branch member into the cylinder, tubes connecting the side branches of 10 said three-branch member with the tube connecting the lower end of the cylinder with its respective water intake and with a side orifice in the top portion of the cylinder, each of the last mentioned connection tubes being provided with a check valve, two plungers fitted within the cylinder and connected by a rod and of which the upper plunger is connected with said stem, and means for causing the slideable movement of 15 the stem in opposed directions.
- 20 2. A mechanical apparatus for raising a continuous stream of liquid, according to claim 1, wherein the central branch of the upper three-branch member is connected with the upper cap of the cylinder by a nipple screwed on said central branch and welded to said upper cap, said cap having a central hole loosely lodging the slideable stem and about the latter a water press-joint comprising an upper press member 25 screwed on the threaded inner surface of the cap, a packing filling, and a lower nut screwed on the inner surface of said cap to obturate inferiorly the central hole of said cap.
- 30 3. A mechanical apparatus for raising a continuous stream of liquid, according to claim 1, wherein each of the plungers is composed of an outerly threaded core having a head, a series of inter-spaced leather washers disposed on said core, ring nuts screwed on the core alternately 35 to said washers, and a nut screwed on the reduced end of the core to tighten the hole formed by said washers and ring nuts upon the core.
- 40 4. A mechanical apparatus for raising a continuous stream of liquid, according to claim 3, 45 wherein half of the leather washers of each plunger are in an inverted position relatively to the other half of the washers of same plunger, and the washers of one plunger are in inverted position relatively to those of the other plunger.
